UNITED STATES PATENT OFFICE.

CARRIE E. TAYLOR, OF LOS ANGELES, CALIFORNIA.

FRAMING AND ATTACHING MEANS FOR WINDOWS.

1,372,048.

Specification of Letters Patent. Patented Mar. 22, 1921.

Application filed March 2, 1917. Serial No. 152,059.

To all whom it may concern:

Be it known that I, CARRIE E. TAYLOR, a citizen of the United States, resident of Los Angeles, in the county of Los Angeles and State of California, have invented certain new and useful Improvements in Framing and Attaching Means for Windows; and I do hereby declare the following to be a full, clear, and exact description of the invention, such as will enable others skilled in the art to which it appertains to make and use the same.

This invention relates to improvements in framing and attaching means for windows and more particularly to such as are adaptable for use on automobile tops,—one object of the invention being to so construct devices of the character specified that the parts thereof may be readily connected with supporting means and removably secured together by fastening means which shall be concealed.

With this and other objects in view, the invention consists in certain novel features of construction and combinations of parts as hereinafter set forth and pointed out in the claims.

In the accompanying drawings; Figure 1 is a view illustrating an application of my improvements; Fig. 2 is a face view, with one of the frame members removed; Fig. 3 is an inside face view of one of the frame members, Fig. 4 is a sectional view on the line 4—4 of Fig. 2, and Fig. 5 is a section on the line 5—5 of Fig. 2.

My improved frame and window attaching device may be made in any desired shape but in the drawings I have shown the same as being oval.

1 and 2 represent the respective frame members and may comprise sheet metal strips and these frame members or strips may be made convex or of any other desired contour to present a neat appearance. Both frame members may be made concavo-convex in cross section, and the frame member 1 may be provided with an interior flat base portion 3 from which numerous pointed teeth 4 may project, said teeth being caused to penetrate the material 5 of the automobile top, around the window opening therein, and then bent over as shown in Fig. 2, thus securing the frame member 1 to said material.

A plurality of button members 6 project from the base portion 3 of the frame mem-

ber 1 and through the material 5, and the frame member 2 is provided therein with a corresponding number of sockets 7 to receive the button members 6. Either the button members 6 or the walls of the sockets 7 may be made resilient in character, so that when button members engage in the sockets, the two frame members will be removably secured together. In the drawings, I have shown the button heads as being solid and the walls of the sockets split to cause the same to be resilient.

Before the frame members are assembled as above stated, a transparent window 8 of glass, celluloid or other suitable material will be placed in position to cover the window opening and may be held in place by suitable clips 9 secured to the frame member 1.

It will be observed that when the frame members are assembled, the fastening means which unite said frame members are wholly concealed by the latter, and that said frame members also act to conceal the fastening means whereby the device is secured to the material of the automobile top and also the fastening means whereby the transparent window is held in place.

Various changes might be made in the details of construction of my invention, without departing from the spirit thereof or limiting its scope and hence I do not wish to restrict myself to the precise details herein set forth.

Having fully described my invention what I claim as new and desire to secure by Letters-Patent, is:—

1. A device of the character described, comprising two frames to receive an edge portion of material of an automobile top and an edge portion of a transparent pane between them, fastening devices carried by one of said frames to engage said material, separate holding devices carried by said frame to engage said pane and retain it in position thereon, and separable fastening devices having their respective members secured to the respective frames, whereby said frames are removably connected together and normally conceal all of said fastening means.

2. A device of the character described comprising a base frame and a covering frame to receive an edge portion of the cloth for an automobile top and an edge portion of a transparent window pane between them,

- said base frame provided between its edges with fastening devices to engage said cloth and secure the base frame thereto, fastening devices secured to said base frame between 5 the edges thereof and adapted to engage said transparent pane, one member of a plurality of separable fastening devices secured to said base frame between the edges thereof, and the other members of said separable fastening devices secured to the covering frame between the edges thereof, all of said fastening devices being concealed by said frames and between the respective edges of each of them.
- 10 3. A device of the character described, comprising a frame having an inner base
- 15

portion, teeth projecting from said base portion to secure said frame to the cloth of an automobile top, clips secured to said base portion for holding a window pane in place, 20 another frame, means separably connecting the same to the first-mentioned frame, said separable frame concealing the connecting means for the frames and also the teeth and clips on the first-mentioned frame. 25

In testimony whereof I have signed this specification in the presence of two subscribing witnesses.

CARRIE E. TAYLOR.
